US00D969598S

(12) **United States Design Patent** (10) Patent No.: **US D969,598 S**
(45) Date of Patent: **** Nov. 15, 2022**

(54) **TUBE SECUREMENT DEVICE**

(71) Applicant: **3M INNOVATIVE PROPERTIES COMPANY**, Saint Paul, MN (US)

(72) Inventors: **James M. Sieracki**, Plymouth, MN (US); **Michael J. Turnbull**, Woodbury, MN (US); **Denise J. Ziemann**, Fridley, MN (US); **Kimberly A. Schommer**, Hudson, WI (US); **Amanda C. Engler**, Woodbury, MN (US)

(73) Assignee: **3M Innovative Properties Company**, St. Paul, MN (US)

(**) Term: **15 Years**

(21) Appl. No.: **29/693,315**

(22) Filed: **May 31, 2019**

(51) LOC (13) Cl. **08-08**

(52) U.S. Cl.

CLAIM

The ornamental design for a tube securement device, as shown and described.

DESCRIPTION

FIG. 1 is a perspective view showing the new design for a tube securement device;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the drawings depict features of the tube securement device that form no part of the claimed design.
